UNITED STATES PATENT OFFICE.

FRANK J. YEIP, OF CLEVELAND, OHIO.

PACKING BOX.

Application filed November 23, 1921. Serial No. 517,292.

To all whom it may concern:

Be it known that I, FRANK J. YEIP, a citizen of the United States, residing at Cleveland, in the county of Cuyahoga and State 5 of Ohio, have invented certain new and useful Improvements in Packing Boxes; and I do hereby declare the following to be a full, clear, and exact description of the invention, such as will enable others skilled in the art 10 to which it appertains to make and use the same.

This invention relates to new and useful improvements in packing boxes and more particularly to what is known as a floating 15 stuffing or packing box adapted to be used on any rotating or reciprocating rod that requires packing, the main object of the present invention being the provision of a floating casing or packing box adapted to 20 be applied to the rod support whether it be a cylinder or the like and provide suitable packing for the movement of the rod, said casing being arranged so that it may readily adjust itself to alignment of the rod and 25 also vibrate with the rod thus relieving the strain from the packing of the rod.

Another object of the invention is the provision of a floating stuffing or packing box wherein all wearing parts can be quickly 30 and readily renewed at very little cost and wherein the same will adapt itself to a very high pressure without cutting or wearing the rod.

A further object of the invention is the provision of a stuffing or packing box of the 35 above character whereby the parts which retain the box in position are provided with suitable lubricant whereby to eliminate any wearing on the parts during the vibration or movement of the casing whereby the casing may move or vibrate very readily and be retained in alignment with the rod which works therein.

With the above and other objects in view 40 the invention consists in the novel features of construction, combination and arrangement of parts hereinafter more fully set forth, pointed out in the claim and shown in the accompanying drawings, in which:

50 The drawing illustrates a longitudinal sectional view taken through my improved stuffing or packing box with the rod in position, the stuffing or packing box being illustrated here as applied to the end of a cylinder.

55 Referring now more particularly to the

drawing, the numeral 1 indicates a portion of a cylinder casing having the usual rod opening 2 and is further provided with a cavity 3 communicating with the rod opening 2 and preferably cylindrical in form.

The movable rod which is generally indicated by the numeral 4, is mounted within the opening 2 of the cylinder and extends out through the cavity 3. In the present instance, the rod is illustrated as supposedly of the reciprocating type and surrounding the rod is a packing box or casing 5, the inner end of said casing being arranged within the cavity 3 and adapted to entirely 70 surround the rod 4. The casing or housing 5 is provided with an annular recess 6 terminating into a shoulder 7 and arranged within this annular recess 6 is the packing material 8. This packing material or stuffing may comprise flexible metallic packing, fiber packing or metal rings in accordance with the requirements desired. The casing or box 5 is provided intermediate of its ends with an annular flange 9 adapted to rest 80 against the end of the cylinder 1 to retain the box 5 against inner movement.

The casing or box 5 is retained in position within the cavity 3 by means of a removable collar 11 which is angular in cross section as 85 illustrated, one side of the collar bearing against the outer face of the cylinder 1, while the other end projects inwardly toward the casing 5 over the flange 9 and as this collar 11 is bolted to the cylinder 1 90 through the medium of the bolts 12, it will securely retain the casing 5 in position within the cavity 3. Disposed between the inner edge of the collar 11 and the end of the cylinder 1 are suitable liner rings 10, one 95 or more of which can be removed to compensate for the wear upon the inner or outer face of the flange 9. In assembling the device, the casing or box 5 is placed in position over the rod 4 and moved into the cavity 3 100 until the flange 9 contacts with the outer end of the cylinder 1. The collar 11 is then moved over the outer end of the casing 5 until it contacts with the flange 9, the nuts 13 are then threaded upon the bolts 12 to 105 retain the collar 11 in position and hold the casing 5 within the cavity 3.

It will be noted in the drawing that the outer end of the casing or housing 5 is provided with screw threads 14 and mounted 110 upon this threaded portion of the casing or stuffing box 5 is a removable flange 15. In

order to prevent rotating movement of the casing 5 beyond a certain predetermined distance a suitable pin or pins 16 are threaded through the flange 15 and adapted 5 to engage with and seat in sockets 16' in the collar 11 to hold the same in position after the flange 15 has been screwed down tightly upon the outer end of the stuffing box 5.

After the stuffing box 5 has been placed 10 in position within the cavity 3, surrounding the rod 4, the packing 8 is then placed in position within the recess 6 and in order to retain the packing in position and keep the same under proper pressure, a movable 15 sleeve 17 is mounted within the stuffing box at the outer end of the recess 6 and in order to adjust this sleeve 17 within the stuffing box, a flange 18 is formed upon the outer end of the sleeve 17 through which the adjusting bolts 19 project, said adjusting bolts being carried by the flange 15. The adjusting bolts 19 are threaded into the flange 15 and extend up through the flange 18 and suitable nuts 20 are mounted upon the outer 20 ends of the bolts whereby turning movement of the nuts 20 will force the flange 18 inwardly toward the flange 15, thus moving the sleeve 17 inwardly against the packing 8.

It will be noted that in placing the stuffing box 5 in position around the rod 4, there is considerable clearance between the walls of the cavity 3 and the exterior of the stuffing box and that suitable clearance is 25 provided between the collar 11 and the flange 9 as well as that portion of the stuffing box which is arranged adjacent the collar 11 whereby through any vibrating movement on the part of the rod 4, the stuffing box 5 may move with the vibrations of the rods so as to retain the alignment of the stuffing box with respect to the rod so as to keep the packing 8 into close contact with the rod 4 at all times.

As a general rule, greater or less wear is bound to occur at the point where the rod 4 extends through the opening 2 in the cylinder and in order to provide means whereby the stuffing box 5 will be retained in 40 proper alignment with the rod 4 the stuffing box 5 is provided with a certain amount of clearance with respect to the walls of the cavity 3 so that this wear may be readily taken care of. It will be noted that through 45 the vibration of the rod 4, the flange 9 will move laterally between the end of the cylinder 1 and the inwardly projecting portion

of the collar 11 and in order to provide for the proper lubrication of the flange 9, pressure lubricating means in the shape of a 60 cup 21 is provided having a stem 22 communicating with the space between the collar 11 and the flange 9.

In the drawing, I have illustrated the inwardly projecting flange portion of the collar 11 as provided with an annular cavity in which a packing ring 23 is placed, the outer surface of this packing ring contacting with the outer face of the flange 9 whereby to prevent any leakage from the 70 cylinder 1 at this point. While I have shown and described this packing ring 23, the same is not absolutely necessary and can be eliminated if desired.

From the above description taken in connection with the accompanying drawings, it will be readily apparent that I have provided an improved stuffing box of the floating type wherein all of the parts thereof can be quickly and readily taken apart and 75 reassembled in a very short space of time and wherein the packing generally indicated by the numeral 8 can be readily removed and replaced when desired. It will also be noted that the packing or stuffing 80 box 5 will be retained in alignment with the rod 4 at all times regardless of the movement of the rod whereby the proper amount of lubricant will be applied to the rod 85 throughout all of its movements.

In order to prevent rotating movement of the case 5 with its assembled packing 8, flange 15 and glands 17 and 18 beyond a certain predetermined distance, suitable pins 16 are threaded through the flange 15 and 90 project loosely into collar 11. The cavities in collar 11 into which pins 16 extend should be as much larger than the pins 16 so as to have the same clearance as packing case 5 has in cavity 3.

I claim:

The combination with a supporting element, of a packing box and rod, a collar adapted to hold said packing box on the supporting element, a threaded flange carried at the free end of said box, and means carried by the threaded flange adapted to prevent rotating movement of the packing box beyond a certain predetermined distance.

In testimony whereof I affix my signature.

FRANK J. YEIP.
